CLAIM

We claim the ornamental design for a fire barrier assembly, as shown and described.

DESCRIPTION

FIG. 1 is a front perspective view from above of a fire barrier assembly;

FIG. 2 is a top perspective view of the claimed design of FIG. 1;

FIG. 3 is a perspective cross-sectional view from below of the claimed design of FIG. 1, taken along line 3-3 of FIG. 1;

FIG. 4 is a right side view of the claimed design of FIG. 1; FIG. 5 is a left side view of the claimed design of FIG. 1; FIG. 6 is a top view of the claimed design of FIG. 1; FIG. 7 is a bottom view of the claimed design of FIG. 1; and, FIG. 8 is a front view of the claimed design of FIG. 1.

The evenly spaced broken lines depict portions of the fire barrier assembly that form no part of the claimed design. The dot dash broken lines depict a symbolic break in the article. The portion between the break lines forms no part of the claimed design. The width of the symbolic break in FIGS. 3-7 was reduced as compared to the width of the symbolic break in FIGS. 1 and 2 in order to fit the drawings on the page. FIG. 8 was enlarged relative to FIGS. 1-7 for the sake of clarity.

1 Claim, 6 Drawing Sheets
